(57) **CLAIM**

The ornamental design for a vehicle mirror, as shown and described.

DESCRIPTION

FIG. 1 is a front perspective view of the claimed design for a vehicle mirror;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The uneven-length broken line immediately adjacent to the shaded area defines the bounds of the claimed design and forms no part thereof. The even-length broken lines depict the remainder of the vehicle mirror and form no part of the claimed design. The oblique line shading represents that the surfaces have a transparent, translucent, or reflective appearance.
